UNITED STATES PATENT OFFICE

123,716

DESIGN FOR AN ELECTRIC SAFETY SWITCH

Antonio C. Heisinger, Santiago, Cuba

Application January 29, 1940, Serial No. 89,866

Term of patent 14 years

To all whom it may concern:

Be it known that I, Antonio C. Heisinger, a citizen of Germany, residing at Santiago de Cuba, have invented a new, original, and ornamental Design for an Electric Safety Switch, of which the following is a specification, reference being had to the accompanying drawing, forming part thereof, wherein:

Figure 1 is a front perspective view of an electric safety switch, showing my new design.

Figure 2 is a reverse perspective view.

Figure 3 is a bottom plan view.

I claim:

The ornamental design for an electric safety switch, as shown.

ANTONIO C. HEISINGER.
